UNITED STATES PATENT OFFICE.

FREDERICK J. EDGARS, OF BROOKLYN, NEW YORK.

DESIGN FOR A BOX.

SPECIFICATION forming part of Design No. 23,848, dated December 4, 1894.

Application filed October 31, 1894. Serial No. 527,587. Term of patent 7 years.

To all whom it may concern:

Be it known that I, FREDERICK J. EDGARS, a citizen of the United States, residing at Brooklyn, in the county of Kings and State of New York, have invented and produced a new and original Design for a Wooden Box, of which the following is a specification.

- In the drawing I have represented my design by an elevation and partial section.
- 10 The general configuration of the box is round, and the leading features of my design consist in the rounded central bands, the plain portions above and below the bands, the rounded top and curved base.
- 15 The design of the cover A comprises the rounded top *a*, the curved rib *b*, the plain par-

allel sided portion *c*, and the curved central bands *d*.

The design of the body portion B comprises the plain tapering portion *e* with rounded base *e'*, the cove *f*, the curved base *g* and the plain bands *h i*.

What I claim is—

The design for a wooden box substantially as shown and described.

Signed by me this 29th day of October, A. D. 1894.

FREDERICK J. EDGARS.
